UNITED STATES PATENT OFFICE.

JOHN ROGERS, OF NEW CANAAN, CONNECTICUT.

DESIGN FOR A GROUP OF STATUARY.

SPECIFICATION forming part of Design No. 15,807, dated February 10, 1885.

Application filed January 2, 1885. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying drawings, forming part thereof.

10 The group is in illustration of Longfellow's poem of the "Courtship of Miles Standish," where John Alden is urging the suit of Miles Standish, who wishes to marry Priscilla. After listening to him, she says: "Why don't 15 you speak for yourself, John?" I take this point in the description, and the design shows Priscilla seated on an old-fashioned settle and with a spinning-wheel in front of her. Her head is turned toward John Alden, who stands on her right hand, resting his right elbow on 20 a high-backed chair in front of him. He holds his broad-brimmed hat in his hands, and is dressed in the Puritan costume. His face is turned toward Priscilla.

What I claim as my invention, and wish to 25 secure by Letters Patent, is—

A group of statuary consisting of a girl seated on a bench with a high back to it, with a spinning-wheel in front of her, and a man dressed in Puritan costume standing behind a 30 chair on the right hand of the girl, the faces of both turned toward each other, all of which is herein shown and described.

JOHN ROGERS.
